UNITED STATES PATENT OFFICE.

ARTHUR O. HUBBARD, OF MINNEAPOLIS, MINNESOTA.

FOLDING BOX.

SPECIFICATION forming part of Letters Patent No. 606,459, dated June 28, 1898.

Application filed December 21, 1897. Serial No. 662,787. (No model.)

To all whom it may concern:

Be it known that I, ARTHUR O. HUBBARD, of Minneapolis, county of Hennepin, and State of Minnesota, have invented certain new and useful Improvements in Folding Boxes, of which the following is a specification.

My invention relates to folding boxes adapted for use in delivering or shipping articles of merchandise from place to place; and the object of the invention is to provide a box of light material, but of very strong and durable construction, which may be folded up when empty into a compact form to occupy but little space, and therefore be especially adapted for use in delivering groceries from house to house or in transporting fruit and vegetables to the market.

A further object is to provide boxes which when used with others of a similar construction may be tiered or piled one upon another without danger of tipping over and spilling their contents.

A still further and important object of the invention is to provide a simple and convenient means for connecting the ends and sides of a folding box which will permit the use of machines in setting up the same and enable box-manufacturers to utilize small pieces of lumber which ordinarily are used for fuel.

The invention consists of a box made up of a series of narrow slats or boards and means for securing the same together and of corner-posts contained within the body of the slats.

The invention further consists in a box having side and end walls, plates secured thereto at the corners of the box, and lacing-wires passing vertically through said plates and through the walls of the box.

The invention consists, further, in providing pivot-pins, also passing vertically through the plates and walls of the box, whereby the abutting ends of the box are pivotally connected.

The invention consists, further, in various constructions and in combinations of parts, all as hereinafter described, and particularly pointed out in the claims.

In the drawings forming part of this specification, Figure 1 is a perspective view of a folding box embodying my invention. Fig. 2

is a similar view with the box partially folded. Fig. 3 is an edge view of the box when folded. Fig. 4 is a sectional view of one corner, showing the means for pivotally connecting the sides and ends at two diagonal corners. Fig. 5 is a sectional view showing the means for connecting the sides and ends at remaining corners. Fig. 6 is a detailed sectional view showing a modified form of pivot-pin. Figs. 7, 8, and 9 are modifications of the hinge-plates. Fig. 10 shows another means for securing the bottom stops.

In the drawings, 2 2 and 3 3 represent, respectively, the narrow strips or pieces composing the sides and ends of the box. These may be of any suitable material, such as bass-wood or oak, and I prefer to construct each side and end of several narrow pieces to render the box stronger and more durable at the corners where the sides and ends are hinged together and at the same time enable the manufacturer to utilize waste lumber.

If preferred, the sides and ends may each be formed in a single piece and the box when so made strengthened at the corners by arranging the plates, hereinafter described, in saw-slits provided at the corners at intervals between the top and bottom of the box. I have found, however, that more waste material could be utilized and a more serviceable box obtained by making the sides and ends of several narrow pieces or strips firmly secured together.

For joining the sides and ends at two diagonal corners of the box I provide flat or strap hinges comprising plates 4 4 and 5 5, arranged in recesses in the edges of the sides and ends at the top and bottom of the box. I also prefer to arrange these plates at intervals in the corners between the pieces or strips comprising the sides and ends to strengthen the corners and to prevent the wear resulting from the rubbing together of the parts composing the sides and ends when the box is in use. These plates are held firmly in position by long staples or lacing-wires 6 6, which are inserted into holes provided in the plates at the top of the box, and after passing down through the sides and ends and the intermediate plates are bent back over the bottom plates and clenched, thereby locking the

plates and the parts composing the sides and ends firmly together. The plates are countersunk to receive the ends of the staples or lacings 6 6 to add to the appearance of the 5 corners and prevent damage to the boxes when piled one upon another. The other ends of the plates 4 4 are offset slightly to overlap the ends of the plates 5 5 and are provided with holes which register with correspondingly-shaped holes in said plates 5 5. 7 7 are pivot-pins or rods, preferably of larger gage than the lacing-wires and which pass through the holes in said plates and down through the ends of the side pieces 2 2 and are headed at 10 each end, thereby locking the parts firmly in position and with said plates, forming hinges whereon the sides and ends swing when the box is folded or unfolded. At the diagonally opposite corner of the box I provide a similar 15 construction.

In order that the box may be folded into a compact bundle and to provide a space for the swinging bottom between the sides and ends when folded, it is necessary to employ 20 a different construction at the remaining diagonal corners. This construction consists in providing angle irons or plates 8 8, having lateral extensions 9 9 at one end, which overlap the ends of the box. These plates are 25 also arranged at the top and bottom of the box and at intermediate points between the pieces or strips composing the sides and ends in recesses provided in the edges of said parts, and the main portions 8 8 are locked firmly 30 in position by facing-wires 10 10, which pass down through the sides of the box and the intermediate plates, and after passing through the bottom plates are bent over and clenched. The lateral extensions 9 are provided at their 35 outer ends with holes or openings to receive pivot pins or rods 11 11, also of larger gage than the lacing-wires, and which pass down through the extensions provided on the intermediate and bottom plates through the ends 40 of the box and are then headed at each end, thereby locking the end parts together and forming a pivot whereon these parts are swung when the box is folded or unfolded. The pivot-pins 11 11 are placed a sufficient distance 45 from the sides of the box to provide a space between the sides when folded corresponding to the thickness of the swinging bottom for the purpose heretofore described. The diagonally opposite corner is provided 50 with similar plates secured together and to the sides and ends in a similar manner.

In Fig. 6 I have shown a slightly-modified form of pivot-pin, which consists in bending the ends over and clenching them instead of 55 forming a head at each end.

Upon one of the side pieces 2 2 on the inside of the box, near the bottom thereof, I provide staples or eyelets 12, through which pass similar staples or eyelets 13, arranged 60 in the edge of the bottom board or plate 14. This board or plate swings on the hinges formed by the staples 12 and 13, and when

the box is unfolded drops to a horizontal position until its ends strike the stops 15, provided on the end pieces 3 3 at the bottom 70 of the box. These stops 15 not only prevent further movement of the bottom 14, but aid in supporting the weight of the material that may be placed in the box. When it is desired to fold the box, the bottom 14 is raised to a 75 vertical position against the side to which it is secured, and one end and side are folded down over the bottom until the sides and ends are parallel, as shown in Fig. 3. At each end of the box nearest the top I provide the hand-holes 16 to aid in handling the box, and in the upper edge of the side and ends, near the middle portion thereof, are the transverse slots 17 and 18, and dowel-pins 19 and 20 are provided upon the lower edge of the box. These 80 dowel-pins dropping into the transverse slots when the boxes are piled one upon another will prevent them from sliding in either direction and spilling their contents.

In Figs. 7, 8, and 9 I have shown a modification of the hinge-plates that are provided at the corners of the box. The modification consists in extending the edges of the plates down over the sides of the box, forming the flanges or lips 21, which are turned in slightly 95 to clamp the upper edge of the slats or strips composing the sides and ends of the box to prevent the same from splitting when the lacing-wires are drawn through the strips or slats or when the box is subjected to a severe strain. 100

In Fig. 10 I have shown a slight modification of the manner of securing the stops 15 to the inside of the box at its lower edge. This change consists in providing a flange 22 at the upper edge of each stop to enter a slot provided in the end strips and having openings through which the lacing-wires pass to hold the stop securely in position.

It will be noted that the ends and sides of the box, as shown in the drawings, are each 110 composed of four strips of substantially the same width, the upper edge of the bottom slats representing a fraction of a bushel, the upper edge of the second slats representing another fraction, and so on, so that the box 115 may be used as a measure as well as a receptacle for use in delivering or marketing vegetables and articles of merchandise.

The advantages of this form of hinge for connecting the sides and ends of a folding 120 box lie in the fact that narrow comparatively thin material may be used which would not be suitable for manufacturing folding boxes made in the ordinary manner on account of the danger of the wood's splitting at the corners and loosening the hinges, and thereby rendering the box unfit for use. Furthermore, the use of the wire lacings enables the manufacturer to use machines in setting up the boxes, thereby cheapening the cost of the 125 production, and the use of long pivot-pins, which extend entirely through the sides and ends of the box, greatly increase the strength and efficiency of the hinges, besides adding 130

materially to the strength and durability of the corners of the box.

Having thus described my invention, I claim as new and desire to secure by Letters Patent—

1. The combination, in a folding box, with non-overlapping side and end walls, of hinge-plates secured to the upper and lower edges of said walls and overlapping the same, and pivot pins or rods passing through said plates and vertically through said walls, substantially as described.

2. The combination, in a box, with the sides and ends, each composed of a series of strips or slats placed one above the other, of plates arranged between said strips and upon the upper edges of the top strips and the lower edges of the bottom strips and overlapping said sides and ends, and lacing-wires passing vertically through said plates and through said strips or slats, substantially as described.

3. The combination, in a folding box, with the sides and ends, each composed of a series of strips or slats placed one above the other, of plates arranged between said strips and upon the upper edges of the top strips and the lower edges of the bottom strips, and overlapping said sides and ends, lacing-wires passing vertically through said plates and through said strips or slats, and pivot pins or rods also passing through said plates and said strips, substantially as described.

4. The combination, in a folding box, with the sides and end walls, of hinges secured to the upper and lower edges of one of said abutting walls at each corner of the box, said hinges composed of horizontal plates overlapping the abutting walls, and pivot pins or rods passing through the free ends of said plates, and vertically through the walls, for the purpose set forth.

5. The combination, in a folding box, with the sides and ends, of plates or straps arranged at intervals in the sides and ends at the corners of said box, and at the top and bottom thereof, means for securing said plates in the corners of the box, said plates overlapping the abutting sides and ends, and pivot-pins passing through said plates and vertically through the walls at the corners of the box, substantially as described.

6. In a folding box, the combination, with the sides and ends, of plates 4, 4, and 5, 5, arranged at two diagonal corners of the box, said plates having overlapping ends, and lacing-wires passing through said plates and vertically through said sides or ends, and pivot pins or rods passing through the overlapping ends of said plates, and vertically through the walls at the corners of the box, and angle irons or plates pivotally arranged at the other diagonal corners, substantially as described.

7. In a folding box, the combination, with the sides and ends, of plates 8, 8, having lateral extensions 9, 9, arranged at two diagonal corners of the box, lacing-wires whereby said

plates are secured to the sides of the box, pivot pins or rods passing through said extensions 9, 9, and through the ends of the box and whereon the sides and ends are swung when the box is folded or unfolded, substantially as described.

8. The combination, in a folding box, with the sides and ends, of plates or straps secured to said sides and ends at the corners of the box, pins or rods passing through said plates and vertically through said sides and ends and forming pivots whereon the same are swung when the box is folded or unfolded, slots provided in the upper edges of said sides and ends, and dowel-pins in the lower edges of the same, for the purpose set forth.

9. In a folding box, the combination, with the sides and ends, of the angle irons or plates secured at two diagonal corners of the box, 85 said irons comprising plates 8, 8, having the lateral extensions 9, 9, pivot-pins passing through said extensions and vertically through the ends of the box, a swinging bottom, the distance between said pivot-pins and the sides of the box corresponding substantially to the thickness of said bottom, for the purpose set forth.

10. The combination, in a folding box, with the sides and ends, composed of a series of strips or slats placed one above the other, of plates arranged between said strips and upon the upper edges of the top strips and the lower edges of the bottom strips and overlapping said sides and ends, lacing-wires passing vertically through said plates and through said strips or slats, and the lips or flanges provided upon the edges of said plates, for the purpose set forth.

11. The combination, in a box, of a series 105 of slats or narrow boards making up each side and end thereof, hinge-plates overlapping the abutting side and end walls, and metallic fastenings included by the thickness of said slats or boards and passing through the same and said plates to secure them together, substantially as described.

12. The combination, in a box, of a series 115 of slats or narrow boards making up each side and end thereof, and metallic fastenings included by the thickness of said slats or boards and between the same for securing them together, and means having fastenings within the body of the slats or boards and pivoting the sides and ends, substantially as 120 described.

13. The combination, in a box, with non-overlapping side and end walls, of hinge-plates arranged at the corners of the box and included in the thickness of said walls and overlapping their abutting ends, and metallic fastenings passing through said plates and vertically through said walls, substantially as 125 described.

14. In a folding box, the combination, with 130 side and end walls and a swinging bottom, of plates included between the inner and outer

surfaces of said walls and overlapping their abutting ends, pivot-pins passing through said plates and vertically through said walls at or near the apexes of two diagonal corners and in the remaining diagonal corners at a distance from their apexes corresponding substantially to the thickness of said bottom.

In testimony whereof I have hereunto set my hand this 15th day of December, A. D. 1897.

ARTHUR O. HUBBARD.
In presence of—
RICHARD PAUL,
A. F. HOLMES.
